(57) **CLAIM**

The ornamental design for a box, as shown and described.

DESCRIPTION

1. Box
- 1.1 : Perspective
- 1.2 : Front
- 1.3 : Back
- 1.4 : Left
- 1.5 : Right
- 1.6 : Top
- 1.7 : Bottom
- 1.8 : Reference

The materials of box are paper and synthetic resins; this box is for storing various cosmetic containers and items; figure 1.1 shows the perspective view; figure 1.2 shows the front view; figure 1.3 shows the back view; figure 1.4 shows the left side view; figure 1.5 shows the right side view; figure 1.6 shows the top plan view; figure 1.7 shows the bottom plan view; 1.8 is an open perspective view. Throughout the reproductions, the letters and the numbers shown form no part of the claimed design.

1 Claim, 8 Drawing Sheets
